CONTAINER FOR THE IMMERSION OF CONTACT LENSES

Philomena F. Di Petrillo, 147 Friendly Road, Cranston,
R.I., and Edmund V. Merlan, 43 Greenlake Drive,
Greenville, R.I.

Filed Dec. 31, 1964, Ser. No. 83,246

Term of patent 14 years

(Cl. D57—1)

FIG. 1 is a perspective view of a container for the immersion of contact lenses showing our new design;
FIG. 2 is a side elevational view thereof;
FIG. 3 is a top plan view thereof;
FIG. 4 is a bottom plan view thereof;
FIG. 5 is a section taken on line 5—5 of FIG. 2; and
FIG. 6 is an end view thereof.

We claim:

The ornamental design for a container for the immersion of contact lenses, substantially as shown and described.
